Filed Dec. 29, 1967, Ser. No. 9,993

Term of patent 14 years

U.S. Cl. D54—12
Int. Cl. D7—03FIG.1.

FIG.2.

FIG.3

FIG.4.

FIG.5.

FIG. 1 is a front elevational view of a fork showing my new design;

FIG. 2 is a rear elevational view;

FIG. 3 is a side elevational view;

FIG. 4 is a cross sectional view taken on line 4—4 of FIG. 1; and

FIG. 5 is a cross sectional view taken on line 5—5 of FIG. 1.

The essential features of my design for a fork or similar article of flatware reside in the configuration of the handle in combination with the particular pattern of surface ornamentation applied thereto. The simulations of leaves are raised on the surface and have incised lines with the stippling of the background indicating textured surface treatment.

The design is intended for use on sets comprising forks, spoons, knives and similar articles of flatware.

I claim:

The ornamental design for a fork or similar article of flatware, substantially as shown and described.
